UNITED STATES PATENT OFFICE.

UNO L. M. ZETTERSTROM AND CHARLES G. HELSTROM, OF HARTFORD, CONNECTICUT.

TOBACCO-PIPE.

1,082,384.

Specification of Letters Patent. Patented Dec. 23, 1913.

Application filed January 23, 1913. Serial No. 744,761.

To all whom it may concern:

Be it known that we, UNO L. M. ZETTERSTROM and CHARLES G. HELSTROM, residing at Hartford, in the county of Hartford and State of Connecticut, have invented certain new and useful Improvements in Tobacco-Pipes; and we do hereby declare the following to be a full, clear, and exact description of the invention, such as will enable others skilled in the art to which it appertains to make and use the same.

This invention relates to tobacco pipes; and it consists in providing a slideable cleaning device in the stem of the pipe as herein-after fully described and claimed.

In the drawings, Figure 1 is a longitudinal section through a pipe provided with a cleaner according to this invention. Fig. 2 is a cross-section through the pipe stem 20 and the cleaner, drawn to a greatly enlarged size for clearness.

The pipe stem 2 is provided with a straight cylindrical hole 3 which extends through its mouthpiece 4, when a separate mouthpiece is used, and through an extension 5 of the stem on the opposite side of the bowl 6 from the mouthpiece. The hole 3 extends crosswise of the bowl and the bottom 7 of the bowl is arranged level with the bottom of the hole.

A removable tapering plug 8 is provided and is thrust into the front end of the hole 3 in the extension 5, the end portion of the hole being suitably tapered to receive the plug. The plug preferably has a head 9 for convenience in removing it.

The cleaner consists of a long corrugated scraper 10, preferably formed of a flat strip of metal or of any other suitable material. 40 This scraper has angular corrugations the sides of which are inclined in opposite directions alternately in substantially parallel planes, so that angular scrapers 12 are formed which engage with the pipe stem

as shown in Fig. 2, and which scrape out 45 the stem in a very efficient manner and do not obstruct it so that the pipe will not draw freely. These angle-shaped scrapers are revolved by means of the plug when the cleaner is partially removed, and the scrapings are caught in the corrugations and are removed by pulling out the cleaner. When a spiral cleaner is used, it rubs the dirt against the sides of the stem and does not scrape it off as efficiently as the angle-shaped 55 scrapers. This corrugated scraper is secured at one end to the plug 8, and it extends longitudinally in the hole 3 through the bottom portion of the bowl of the pipe to within a short distance of the front end 60 of the mouthpiece. The corrugated scraper is proportioned to the hole 3 so that it will bear against the sides of the hole but will not obstruct it so that the pipe will not draw. 65

The pipe stem and the bottom of the bowl are cleaned out and freed from obstructions by revolving the scraper and withdrawing it from the hole.

What we claim is:

The combination, with a tobacco pipe having a hole in the front end of its bowl in line with its stem, of a plug inserted in the said hole, and a cleaner formed of a flat strip provided with angular corrugations the sides of which are inclined in opposite directions alternately in substantially parallel planes and which form a series of angle-shaped scrapers the points of which engage with the pipe stem. 75

In testimony whereof we affix our signatures, in presence of two witnesses.

UNO L. M. ZETTERSTROM.
CHARLES G. HELSTROM.
